UNITED STATES PATENT OFFICE.

EMILIO M. FLORES, OF BUENOS AIRES, ARGENTINA.

LIQUID FUEL.

No Drawing. Application filed June 9, 1922, Serial No. 567,170, and in Argentina January 16, 1922.

This invention relates to an improved liquid fuel, particularly suitable for being transformed into motive power by means of any of the known systems of internal combustion engines, being also specially adapted for heating, lighting and other industrial purposes.

The primary material or liquid which forms the base of the novel liquid fuel, for reasons of economy, is obtained from the fermentation of the residues resulting from the elaboration of sugar cane, such as molasses, as well as of those obtained from the sugar beet, potatoes, manioc, grain (damaged or not), cut stalks, plantains, grapes and other fruit, etc.

Heretofore, the direct use of the raw fermentation products containing all of their distillable alcoholic components for industrial purposes of any description has not been practiced.

The industrial use of the aforementioned waste products, for the purpose set forth, may be considered as quite unique, up to this date, and permits of obtaining most important advantages as regards the obtention of the first fuel of this kind, suitable for use.

The new liquid fuel offers the particular condition that it distils at temperatures ranging from 40° C. upwards, and that it may be fractionated as required by the particular use to which it is destined and that said products differ from each other, as to the physical properties, in accordance with the requirements of the different uses above referred to.

It will also be apparent that for each particular use, preferably one particular form or identification of the fuel, distilled at a given temperature, should be employed, of similar chemical composition; this allows of accordingly increasing the useful output, as the amounts of the hydro-carbon bodies consumed in each of said distillations, are entirely constant in apparatus of different yields.

The fuel compound in accordance with this invention is obtained by the following reactions:

1. The result of any alcoholic fermentation, either grouped or separate or sub-groups of same (alcohols up to the poly-valents, saturated or not, in a similar manner and of the same composition as the concomitant secondary products, aldehydic,

ketonic, etc.), obtained by different actions from any material containing carbohydrates, sugar, starch, cellulose, converted by suitable forming processes is distilled to obtain a 60 distillate containing about 90% combustible. As I have already stated above, the essential feature of this invention consists in making use of the fermentation caused in vegetable waste products or in by-products, even 65 though the same should have been damaged or frozen.

2. With varying proportions of para-formaldehyde $(\text{CH}_2\text{O})_2$ and of metaformaldehyde $(\text{CH}_2\text{O})_3$, according to the richness of the fermentations obtained by the above distillation.

3. With varying proportions, similarly, of fractions of mineral oils distilling from density 0.635 to density 0.864; according to 75 the use to which the fuel is to be applied.

4. With proportions, also varying, for similar reasons, of the products of dry distillation of wood, from density 0.792 to 80 density 1.056.

The process is initiated by starting with any dilution of the product of the fermented material, for instance, (a) must, or (b) phlegms; alcohol; head or tail products obtained in the rectifying processes for the separation of ethylic alcohol, etc.; or (c) products of a suitable pyrogenous distillation of any vegetable materials or of certain animal products. The distillate or product shall contain about 90% combustible hydro-carbon compounds resulting from fermentation.

Said liquid or fluid fuel is directly obtained, even though the raw material *a*, *b* has not been submitted to any preliminary 95 distillation for the purposes of concentration, with the addition of the products 2, 3 and 4, the said several ingredients being suitably submitted to maceration during a period of 48 hours, even in the case of the 100 concentrated product of the total fermentations having been diluted in ninety per cent of water.

If the raw material is that of the type *a*, it will be sufficient to cause the direct reaction of the fermented products obtained with the ingredients 2, 3 and 4, the resultant products being separated by fractional distillation at every half degree, according to 105 the use to which they may be destined; this constitutes a particular feature of their obtention, not known heretofore; the said

components should be increased as the degree of dilution of the materials to be converted and distilled increases; such variation of the proportions of the components is of course included within the scope of this invention.

Some fractions of this product, viz: the most dense ones, may also be obtained by using *b*, said concentrated elaborated products, impure alcohols, head and tail products, etc., by simply homologizing the same by means of any of the following physical processes: maceration, barbotage, repeated pouring off, treatment in a centrifugal mill, suitable mixing machines provided with agitators, etc; according to the most economic source of motive power obtainable in the locality where the process is to be carried out.

The resulting product not only possesses the total percentage combustible fermented carbo-hydrates of an entirely different molecular structure, but the same may also be delivered for consumption with a varying additional percentage of 20% or more of distillation water or of water added thereto, according to the conditions of the raw material *a*, *b*, *c*, used in its transformation.

Among the advantages which offers the adoption of this product for the production of motive power, it may be mentioned that 90% of its composition consists of distillates of fermented carbo-hydrates of the raw materials; a complete absence of smoke; no corruptions are caused in the engine, nor is

its operation obstructed by incrustations of carbon; no excessive overheating is caused by its combustion, etc.

A mass containing at least ten percent of fermented and distillable products is filtered and mixed with carbonating materials forming aldehyde and mineral oils to give a density of from .730 to .750 to which is added methyl alcohol having a twenty-five percent acetone content in quantity sufficient to give a distillate having a density of .7801 and a viscosity of 1.08 Engler.

The liquid is limpid, transparent, colorless without particular smell, has a caustic taste.

The liquid analyzes

C	54.971	
H	13.217	
O	31.779	55
Total	99.967	

Having now described my said invention, I declare that what I claim as new and desire to secure by Letters Patent, is:—

The method of making a liquid fuel which comprises mixing a mash containing about ten percent fermented distillable products, filtering the same, adding a distillable carbureting material to produce a density above seven tenths and then adding methyl alcohol containing about twenty five percent acetone to produce a distillate having a density about seventy-eight hundredths.

In testimony that I claim the foregoing as my invention, I have signed my name.

EMILIO M. FLORES.
